[57] **CLAIM**

The ornamental design for a decorative surface for the edge portion of a plate, as shown and described.

DESCRIPTION

FIG. 1 is a front view of a decorative surface for the edge portion of a plate showing my new design;

FIG. 2 is a front view of a decorative surface for the edge portion of a plate showing a second embodiment of my new design embodied in a saucer; and,

FIG. 3 is an enlarged front view of FIG. 1 partially broken away for ease of illustration.

The broken lines shown in the drawings are for illustrative purposes only and forms no part of the claimed design.
